(57) **CLAIM**

The ornamental design for a post-tensioning concrete repair staple, as shown and described.

DESCRIPTION

FIG. 1. is a perspective view of a post-tensioning concrete repair staple.

FIG. 2. is a side elevation view of a post-tensioning concrete repair staple.

FIG. 3. is a front elevation view of a post-tensioning concrete repair staple; and,

FIG. 4. is a top view of a post-tensioning concrete repair staple.

The broken lines in the drawings illustrate portions of the post-tensioning concrete repair staple and form no part of the claimed design.
